UNITED STATES PATENT OFFICE.

EMIL BOMMER, OF BROOKLYN, NEW YORK.

PIVOT HINGE.

Application filed July 5, 1923. Serial No. 649,438.

This invention relates to an improved pivot hinge for doors, gates or the like and is more particularly identified with devices of that character whereby the door is mounted for yieldably resisted swinging movement from a closed position in either direction to an open position.

It is the primary object and purpose of my present improvements to provide a pivot hinge for swinging doors or gates of this class which consists of comparatively few elements of simple and inexpensive construction as well as great durability and which can be easily and quickly applied with a minimum of manual labor.

It is another object of the invention to provide a pivot hinge construction which is equally adaptable to application and use in connection with either right or left hand doors without involving any relative adjustment or rearrangement of the parts.

In one practical embodiment of the invention I provide a stationary pivot post mounted upon the sill of the door frame and spaced parallel plates fixed to the lower edge of the door and having a bearing upon said post. Between these plates I arrange a spring pressed roller and provide guide flanges therefor on the opposite edges of the plates. This roller coacts with cam means formed on the pivot post whereby the spring is placed under tension in the swinging movement of the door to or from its open or closed position. In addition, I propose to provide the pivot post with suitable seats or cavities to receive said roller whereby the door will be held in open or closed position but will readily yield to a positively applied pressure.

With the above and other objects in view my invention consists in the improved pivot hinge and in the form, construction and relative arrangement of the several parts as will be hereinafter more fully described, illustrated in the accompanying drawings and subsequently incorporated in the subjoined claims.

In the drawing wherein I have disclosed one practical and satisfactory embodiment of the invention and in which similar reference characters designate corresponding parts throughout the several views:

Figure 1 is a vertical sectional view illustrating one construction and mounting of my improved pivot hinge;

Figure 2 is a horizontal section taken on the line 2—2 of Figure 1;

Figure 3 is a transverse section taken on the line 3—3 of Figure 1;

Figure 4 is a similar section taken on the line 4—4 of Figure 1;

Figure 5 is an enlarged detail top plan view of the stationary pivot post; and

Figure 6 is a detail perspective view of one of the bearings and guide plates.

In the illustrated embodiment of the invention I have shown only so much of the door structure as is necessary to disclose the manner of application of my present improvement. It will be understood as the description proceeds that the device is applicable to many different types of swinging doors or gates, such as are used between different sections or divisions of a large office, at the entrances to certain commercial establishments, and in numerous other instances.

As herein shown, one of the vertical side bars of the door frame is indicated at 5 and the base or sill bar at 6. To the upper surface of this sill bar at one end thereof depending upon whether the door is mounted in the right or left hand side of the door frame, a metal plate 7 is fixed having a central cupped or dished portion 8, the concave face of which is opposed to the bar 6. This dished part of the plate is provided with a central rectangular opening 9 to receive the square or rectangular lower end 11 of the stationary pivot post 10. The upper end portion of this post is diametrically enlarged as at 12 to provide an annular shoulder 13 thereon. This enlarged section of the post is formed with spaced cam projections 14, the cam surfaces 15 thereof merging into a depression or cavity 16 at one side of the post. At the opposite or outer end of each cam face 15, the projection 14 is formed with a cavity or seat 17, the purpose of which will be presently explained. The upper surface of the enlargement 12 of the pivot post is provided with a bearing ball race 18 surrounding a central upwardly projecting stud 19.

The lower edge of the door 20 is recessed or cut away as at 21 to receive the plates 22 and 23 and the parts arranged therebetween. One end of the plate 22 is bent to provide a relatively long angular extension 24 which is adapted to be securely fixed to

the vertical edge face of the door by the screws 25. The other end of this plate 22 is also angularly bent as at 26 and has a terminal portion permanently fixed in a slot 5 or opening 27 provided in the plate 23. Adjacent thereto one end of the plate 23 is fixed to the door 20 by the screw 28. The other end of the latter plate is permanently fixed as at 29 in a slot or opening in the vertically disposed end 24 of the plate 22. Thus the two plates 22 and 23 are rigidly united to each other to provide parallel portions extending longitudinally within the recess 21 of the door. These parallel portions of 10 the two plates are provided on their opposite longitudinal edges with guide flanges 30. At one end of the flanges 30 and adjacent to the upwardly extending end portion 24 of the plate 22, the latter plate is formed 20 with an opening surrounded by an upwardly projecting boss 31. Through this opening the lower cylindrical portion of the pivot post 10 extends, said boss seating at its upper edge against the shoulder 13 on said 25 post.

The plate 23 is likewise provided with an opening 31 to receive the stud 19 on the upper end of the pivot post, said opening being surrounded by an annular flange 32 with 30 which the anti-friction bearing balls 33 disposed in the race way 18 are engaged.

Between the parallel arms of a yoke 34 a roller 35 is loosely mounted upon a pin 36 connecting the yoke arms. On the ends of 35 this pin exteriorly of the yoke additional rollers 37 are loosely engaged and travel between the guide flanges 30 of the respective plates 22 and 23. The intermediate portion of the yoke 34 is provided with an opening 38 through which one end of a flat 40 rod or bar 39 extends, said end of the bar being angularly bent between the yoke arms and permanently fixed to one of said arms as at 40. This end of the bar 39 is reduced in 45 width providing shoulders 41 thereon which abut against the intermediate portion of the yoke at opposite sides of the opening 38 therein. The other end of the bar 39 is also reduced in width and is loosely engaged 50 through an opening 42 in the upwardly extending end portion 26 of the bar 22. A coil spring 43 surrounds said bar and bears at one of its ends against the end 26 of the bar 22 and at its other end against the intermediate portion of the yoke 34, said spring 55 acting to yieldingly urge the yoke and the roller 35 mounted therein towards the cam projections 14 on the pivot post 10.

In the operation of the device above described, when the gate or door is in closed position as seen in full lines in Figure 2 of the drawings the roller is in opposed relation to the depression or seat 16 between the cam faces 15 and is yieldingly held by the 60 spring 43 in bearing engagement against the

opposite sides of this depression or seat. Thus the door is held against accidental or unintentional swinging movement. However, upon the application of pressure against one side of the door, it may be readily swung in either direction to an open position as seen in dotted lines in Figure 2. In the movement of the door to this position, the roller 35 riding over one or the other of the cam faces 15 is moved laterally with the 70 yoke 34, thereby additionally tensioning the spring 43 which serves at all times to maintain close bearing contact of the roller with the cam face. When the door arrives at its full open position substantially at right angles to the closed position thereof, the roller 35 is forced under the action of the spring 43 into engagement with the cavity or seat 17 at the end of the cam face. Thus it will be clear that the door is also yieldingly retained in this open position against accidental or unintentional swinging movement to a closed position.

In order to protect the several parts of the device, I provide sheet metal cover plates 90 44 which are adapted to be secured to opposite sides of the door over the recess 21 therein. Each cover plate is provided on one end with an angular flange 45 to extend over the end edge of the door and also has a slot or opening 46 through which the bearing 33 for the door structure may be conveniently lubricated. In addition, each plate 44 adjacent its opposite ends is provided with vertically spaced screw receiving openings 47. These spaced openings 95 permit the plates to be readily applied either to right or left hand doors, but at the end of the plate adjacent the pivot post only one screw is inserted through the upper 100 opening 47. These plates provide complete protection for the several operating parts of the device against accumulations of grit or dirt which might possibly interfere with their functional operation.

From the foregoing description considered in connection with the accompanying drawing, the construction and manner of operation of my present invention will be readily understood. It will, of course, be obvious 115 that there is also provided a suitable pivot connection with the upper end of the door which operates to prevent vertical movement of the door and possible detachment of the pivot post 10 from its mounting in the plate 7. It will be seen that this plate holds the pivot post stationary and immovable in the turning or swinging movement of the door and also enables the device to be readily applied without alteration to either right 120 or left hand doors. The improved mounting and arrangement of the sliding yoke and roller with the guide means therefor insures a minimum of frictional resistance and the easy and free operating movement of 125 130

the parts. Also, in view of the simple form and construction of the several elements and their very compact arrangement, relative displacement thereof necessitating more or 5 less frequent repair, is obviated.

While I have herein shown and described an embodiment of my present improvements which has been found very satisfactory in practical operation, it is nevertheless to be understood that the device might also be produced in various other alternative constructions and I accordingly reserve the privilege of resorting to all such legitimate changes in the form, construction and relative arrangement of the several parts as may 15 be fairly embodied within the spirit and scope of the invention as claimed.

I claim:

1. A pivot hinge for doors and the like including a stationary pivot post having spaced cam projections, rigidly connected parallel plates adapted to be mounted in the door structure, each of said plates having parallel guide flanges, a spring pressed yoke positioned between said plates, a roller pivotally mounted in said yoke between the guide flanges on the opposite plates and yieldingly urged into bearing engagement against the cam projections of the pivot post, anti-friction rollers mounted upon the ends of the roller axis and engaged between said guide flanges, said cam projections having seats to receive said roller and yieldingly resist the swinging movement of the door 35 from its open or closed position.

2. A pivot hinge for doors and the like, including a stationary pivot post having spaced cam projections; a spring pressed yoke; a roller mounted in said yoke and yieldingly urged into bearing engagement against the cam projections of the pivot post; guide rollers for the yoke roller; rigidly connected parallel plates adapted to be mounted in the door structure, each of those 45 plates having parallel guide flanges adapted to embrace the said guide rollers.

3. In a pivot hinge for doors and the like having a pivot post: a sill plate secured upon the sill of the door frame, with a central cupped portion and a rectangular hole in it: a lower hinge-case-forming plate, fixed at the door and having an opening with an upwardly extended ring flange adapted to support the lower part of the pivot post: 50 an upper hinge-case-forming plate, fixed at the door and having an opening with a downwardly extended ring flange, adapted to guide the upper end stud of the pivot post and to act at the same time as the upper race 55 of the door supporting ball bearing: said pivot post being provided at its lower part with a neck, which is guided in the ring flange of the opening of the said lower plate, and being provided further at its lower end 60 with a rectangular stud to fit into the rec-

tangular hole of the sill plate, and at its upper end with a cylindrical stud to fit into the ring flange of the opening of the said upper plate, and at its middle part with lateral cam forming projections, adapted to 70 operate the door swinging means, and at its upper part with a door supporting ball bearing: door swinging means arranged between the aforesaid two plates, said means including a spring pressed roller adapted to 75 roll on the said cam-forming projections of the pivot-post, and to exert thereby a lateral door-closing pressure on the aforesaid plates.

4. In a pivot hinge for doors and the like, 80 a swinging frame, a spring pressed plunger carried by said frame, and a stationary pivot-post for the frame, said frame including upper and lower spaced bars having aligned post bearing apertures, said post including 85 upper and lower studs rotatively engaged in said bearing apertures, and a cam projection for co-operation with the spring pressed plunger, and an integral enlargement above said projection provided with an 90 upper circular groove adapted to act as a bearing ball race surrounding said upper bearing stud, and balls interposed between said race and the upper bar of the frame.

5. A pivot hinge for doors and the like, 95 including a stationary pivot post having spaced cam projections, a spring pressed plunger element, a roller adapted to be pressed thereby into bearing engagement with the pivot-post, guide means mounted axially above and below said roller, rigidly connected parallel plates, adapted to be mounted in the door structure, each of said plates having parallel guide flanges adapted to embrace said guide means.

6. In a pivot hinge for doors and the like, 105 a swinging frame, a spring pressed plunger carried by said frame, and a stationary pivot-post for said frame, a sheet metal sill plate adapted to be secured upon the sill of 110 the door frame and comprising a flat sill engaging portion and a central cupped portion provided with a non-circular hole, the convex side of said cupped portion providing a space at the under side of the plate, 115 said pivot-post including a cam projection for co-operation with the spring pressed plunger, and being provided further at its lower end with a non-circular stud of relatively greater length than the metal thickness of said cupped portion of the sill plate 120 and adapted to have non-rotatable engagement in said hole of the plate.

7. In a pivot hinge for doors and the like, 125 a swinging frame, a spring pressed plunger carried by said frame, and a stationary pivot-post for said frame, said frame including upper and lower spaced bars, having aligned post bearing apertures, the aperture 130 of one of said bars having an annular flange

- bent from said bar and constituting a journal bearing of relatively greater length than the metal thickness of the bar, said pivot-post including a cam projection for co-operation with the spring-pressed plunger, and being provided further with cylindrical bearing portions at its upper and lower ends respectively engaged in said apertures of the frame bars.
- 10 8. In a pivot hinge for doors and the like, a swinging frame, a spring pressed plunger carried by said frame, and a stationary pivot-post for the frame, said frame including upper and lower spaced bars having aligned post bearing apertures, the upper aperture having an inwardly bent annular flange pro-
- 5

viding a bearing for the upper end of the post and its under surface providing a ball race, said pivot-post including a cam projection for co-operation with the spring-pressed plunger, bearing portions at its upper and lower ends respectively engaged in said apertures of the frame bars, and a ball race portion in opposed relation to the ball race surface of said flange, and balls 25 interposed between said ball race portion of the post and said ball race surface of the flange.

In testimony that I claim the foregoing as my invention, I have signed my name.

EMIL BOMMER.
